RAILWAY OR OTHER VEHICLES

Edward A. Sweeley, Alexandria, Va., and Norman
T. Anderson, Washington, D. C.

Application July 24, 1936, Serial No. 92,420

14 Claims. (CL 105—376)

This invention relates to improvements in facilities for railway or other vehicles; and more particularly to improvements in wall and bulkhead constructions for use in vehicles. While the invention has particular application to wall and bulkhead constructions for railway cars, it is also applicable to cars, trucks, and ships generally, which require or use bulkheads for similar purposes.

10 In its broadest aspect, the invention relates to a vehicle merchandise chamber having two relatively movable parallel sections which are constructed for nested or interfitted relation in the stored position of the movable section, to provide, in effect, a single wall structure for standard loading within the merchandise chamber. The movable section, when removed from its nested position may be placed in a desired position within the merchandise chamber to serve 15 as a separate bulkhead. This construction offers the peculiar advantages of a sturdy, reinforced movable bulkhead, without sacrifice of a substantial amount of the loading space of the merchandise chamber when the movable bulkhead occupies its stored, nested position.

20 The construction of this invention contrasts with those of the prior art where the movable bulkhead, when stored within the merchandise chamber, occupies cargo space, at least in an amount, corresponding to its three overall dimensions, and where the stored bulkhead leaves an obstructed merchandise chamber, which interferes to some extent with the plane loading space surfaces at the floor, ceiling, four side and end 25 walls.

25 Where the construction of this invention is used between compartments, such as, the ice and merchandise chambers of a railway refrigerator car, for which use it is well adapted, it offers further advantages. For such use, the construction in its nested arrangement provides, in effect, a single wall structure, in which the reinforced movable bulkhead as a part thereof may directly take the thrust of the load or cargo and permit 30 the stationary wall section to be designed principally for the purpose of retaining the ice in the bunker and resisting the deforming stresses of the ice load. The stationary wall section may, therefore, be of lighter construction than would 35 be required if it had to withstand the whole thrust of the load.

35 It is, therefore, an object of this invention to provide for storage of a movable bulkhead within a merchandise chamber, without substantially increasing the size of the chamber and to provide

a maximum amount of loading space when the bulkhead is in the stored position.

40 A further object of this invention is to provide a nested relation between a wall of a merchandise chamber and a movable bulkhead when the latter is placed in stored position within the merchandise chamber.

45 Another object is to eliminate projections within a merchandise chamber, when a movable bulkhead is stored therein.

50 A still further object of this invention is to provide a combined wall structure comprising two closely nesting sections, one of which consists of a fixed wall section or partition, and the other of a bulkhead, which for certain types of shipment 55 may be removed from its nested position and suitably adjusted in a different position within the chamber to serve the function of the usual movable bulkhead.

55 Another object of the invention is to provide 20 a merchandise chamber with an end wall structure which has a thickness approximating that of a conventional wall structure for that part of the merchandise chamber, and which is divided into two parallel nesting sections, one of which is 25 movable to form an intermediate bulkhead within the chamber.

60 A further object is to store a bulkhead in a merchandise chamber so that it leaves a clear cargo space of standard dimensional specifications as to height, width and length. This is an 30 important consideration for shippers who demand this dimensional feature in order to secure maximum loading space for shipping containers which are of a size that is chosen with respect to the 35 said standard dimensional specifications.

65 Other objects and advantages will be apparent from the following detailed description of a preferred embodiment of the invention.

In the accompanying drawings, Figure I is a 40 perspective view of one end of a railway refrigerator car equipped with an embodiment of this invention, the car roof as well as the outer walls and insulation being omitted from the figure for better illustrative purposes.

45 Figure II is a diagrammatic view taken from the side of a railway car having a wall construction embodying this invention and shows the loading space of standard length when the bulkhead is in the nested or stored position. Figure II, for 50 purposes of illustration, shows the nested bulkhead at each end of the merchandise chamber, though generally the nested construction will be provided at only one end of the chamber.

55 Figure III is a horizontal sectional view (with

parts broken away) taken on line III—III of Figure I, and shows in addition a horizontal cross-section through conventional car walls. In this figure, the movable bulkhead is shown in its nested or stored position.

Figure IV is a vertical sectional view taken on line IV—IV of Figure III, but with the movable bulkhead adjusted to a position away from the stationary partition.

10 Figures V and VI are enlarged detail views partly in section and taken on lines V—V and VI—VI respectively of Figure III, parts being broken away for illustration purposes.

15 Figure VII is a perspective view of the bolt housing shown in Figures III and VI.

For the purposes of illustrating this invention, the drawings show a conventional railway refrigerator car provided with a preferred embodiment of the invention. The railway car has the usual 20 arrangement of merchandise chamber or lading space 1, and an ice bunker or chamber 2 at each end.

This invention relates in particular to a wall structure, such as that shown between the chambers 1 and 2. The wall structure referred to comprises two sections 3 and 4 which may be placed in a back-to-back position (see Figure III). In such position, the two sections are in nested or 30 interfitted relation to produce, in effect, a single wall or bulkhead structure with preferably an overall thickness approximately or substantially that of conventional undivided bulkheads, in railway refrigerator cars, between the ice bunkers and the merchandise chamber.

35 Section 3 of the wall structure provides a stationary or fixed partition between the chambers 1 and 2, and its frame structure comprises a number of vertical posts 10 extending between the top and bottom channel-shaped bars or members 12

40 and 11 (see Figures I and IV). Other means, however, may be provided for supporting the ends of posts 10. Suitable means, such as rivets, bolts, or welding may be used to secure the posts 10 to the bars 11 and 12, while the latter are secured

45 respectively to the car floor framing and ceiling by any suitable means, such as bolts. Posts 10 may be of either wood or metal, and, for example, may be formed by stamping or pressing sheet metal to provide flanged channel bars, as shown 50 in the drawings, or other suitable construction. In erected position, as shown for illustrative purposes, the posts 10 present spaced-apart, parallel, channel-shaped recesses or set-back areas with flanges extending laterally from the sides of the

55 recesses. Panels comprising insulation 13 and insulation covering 14 are provided between the posts 10, and these panels are held in place against the post sides and flanges by cleats 15, suitably secured directly to the posts 10. Cleats 15 also

60 serve as a support to which the screen 16 is secured to provide vertical channels or columns 17 for air circulation. In order to permit air circulation between the ice bunkers and merchandise chambers, 2 and 1 respectively, the insulation panels 65 do not extend all the way to the car floor and ceiling, but are of vertical extent to leave upper and lower bulkhead openings 18 and 19 (see Figure IV) for the desired air circulation. Screen 16, however, preferably extends from ice supporting rack or grate (not shown) to ceiling, and serves to confine the ice to the ice bunkers 2, while permitting free circulation of air between the lading compartment and ice bunkers.

70 The movable section 4, which in the illustrated embodiment may be termed an auxiliary bulk-

head, is of such height and width that it can be conveniently shifted relative to the partition-forming section 3, and into a desired adjusted position within the merchandise chamber 1. The movable section or bulkhead 4 comprises principally a facing 25 of wood, or other suitable material, to present a plane loading space wall surface on one side of the bulkhead, and a number of spaced, parallel, upright, frame members 26 projecting from the reverse side of the bulkhead. 10 The members 26 may be of any suitable material and shape, and the metal bars of channel section, as shown in the drawings are considered as a form of reinforcement or bracing that might be used.

These channel bars 26 are spaced laterally in 15 order to register with, and to lie within the channel recesses in posts 10 (see Figure III) when the bulkhead 4 is shifted against the fixed wall-section or partition 3. This arrangement provides a nested or interfitting relation between partition 20 3 and bulkhead 4, in which they together form, in effect, a single wall structure to permit storage of the movable bulkhead 4 in a minimum amount of space. While the drawings show both the members 26 and the recessed uprights 10 for receiving 25 same arranged in a spaced-apart, vertical, parallel design, it is readily apparent that the invention may be practiced with other arrangements for the reinforcing members 26 and the recesses. The important feature is to provide the recesses 30 with such shape, size, and position that they will receive in a nesting relationship the particular projecting reinforcement provided for the movable bulkhead 4.

If desired the bulkhead or movable section 4 35 may be further reinforced, for example, by frame members 27 and 28, of any suitable form, secured to channel bars 26 by means of rivets or the like. Member 27, at the top, may conveniently be an angle bar, and member 28 a flat strap, as shown in 40 Figures I and IV.

In order that the movable bulkhead may permit air circulation in the car, necessary for some types of shipments, the upper and lower limits of the bulkhead facing 25 substantially coincide 45 in extent with those for the insulation panels between posts 10 (see Figure IV). Screen 29 and the spaces above and below strap 28 permit air circulation past the bulkhead 4 at its top and bottom. At the same time, the screen 29 and 50 strap 28 prevent small packages or other merchandise from being pushed or falling past the bulkhead 4 to the space in the rear of the bulkhead when it occupies a position away from partition 3 or when it is in the interfitting position. 55

When a particular shipment does not require refrigeration, and the car is shipped with the ice chambers empty, the merchandise chamber 1 of the refrigerator car is sometimes unlawfully entered by way of the ice bunker 2 and the merchandise pilfered. Screen 29 and strap 28, therefore, serve the additional function of providing effective obstacles at the top and bottom of the bulkhead to unlawful entry into the lading compartment by way of the ice bunkers. 60

The section or bulkhead 4 is suitably supported for convenient shifting movement along the length of the merchandise chamber. The bulkhead supporting means may comprise rollers 40 mounted one at either side of the bulkhead 4, secured 70 adjacent the top thereof and riding on a track 41, set in the side wall of the car, and substantially flush with the face of car lining. Vertical movement of each roller 40 is limited by the height of the wall recess above the track 41, and 75

lateral movement by an upwardly extending, outer, vertical flange of track 41 (see Figure V). The means for securing the rollers 40 to the bulkhead 4 comprises a member 42 (see Figure V) having a horizontal bearing arm extending through an aperture in the web of an outer channel bar 26 to serve as an axle for the roller 40, and a downwardly extending vertical arm suitably secured to the web of the channel bar 26, 5 as by riveting. Rollers 40 and their axles so support the bulkhead 4 that its bottom is supported above the floor rack and the sides of the bulkhead are clear of the car side walls in shifting along the car. Rollers 40 also support the bulkhead 4 so that the channel bars 26 and angle bar 27 will clear the lower edge of the channel bar 12 10 (see Figure IV) when the bulkhead 4 is shifted to nest with partition 3.

In its shifting movement on rollers 40, the bulkhead may be suitably guided at its lower end. This bulkhead guide may comprise the rounded ends of strap 28 which slide in horizontal grooves of the plates 45 set in the car side walls. A suitable roller guide construction of conventional 20 design may be used, however, in lieu of the guide shown in the drawings.

After the bulkhead 4 is adjusted to a desired position, either against partition 3 or in some removed position and within the merchandise 30 chamber 1, it is secured in place by means of one or more locking pins or bolts 50. The latter are mounted in bolt housings 51 secured, as by welding, to reinforcing channel bars 26. In the projected position (see Figures III and VI), each bolt 35 50 extends through an opening in the web of its adjacent channel bar 26, and into a registering aperture in perforated side wall plates 52, the entered aperture corresponding to the position of adjustment of the bulkhead 4. Each bolt 40 50 is held in either its projected or retracted position by a depending lug 53 which engages the intermediate wall 54 of the bolt housing element 51. Before a bolt 50 can be moved toward or from its 45 projected position, it must first be turned on its longitudinal axis through an angle of 180°, in order to bring lug 53 into alignment with the upper elongated portion of opening 55 in the intermediate wall 54 of the bolt housing 51. The bolts 50 and their housings 51 are preferably 50 positioned at the rear of the bulkhead 4 so that the front of the latter is entirely free of projections, and presents the desired plane loading wall surface. In order that the bolts 50 may be operated from the front side of the bulkhead, suitable 55 hand hole openings 56 are provided in the bulkhead facing 25 (see Figures I and III).

The partition 3 and the two outermost posts 10 are modified in certain areas to accommodate the rollers 40, bolts 50, and bolt housings 51, when 60 partition 3 and bulkhead 4 are in the nested relation, as will be seen in Figure III. At the level of the rollers 40, a portion of each of the outermost posts 10 is removed or suitably modified to permit roller 40 to move along on the track 41 65 to a position within the projected limits of partition 3. At the levels of the bolt housings 51, additional or special recesses 57 for receiving them are provided in the partition 3. The outermost posts 10 have areas removed or suitably 70 modified so that a part of the channel recess in a post 10 is a part or continuation of a recess 57 (see Figure III). The end posts 10 also have apertures in alignment with the apertures in plates 52 to receive bolts 50 when the bulkhead 75 4 is to be secured in its nested position.

In one use of the bulkhead 4, for example, where the shipment consists of boxed or crated oranges or other fruit, it may serve as an auxiliary bulkhead to shorten the loading space of the merchandise chamber 1 in accordance with the 5 particular requirements of the shipment. The desired length for the loading space is generally determined by laying end-to-end and in a line, as many of the boxes making up the shipment as the full length of the lading or merchandise 10 chamber 1 permits. Generally, the box at one end of the line will be spaced a distance, for example from 5 to 15 inches, from the adjacent end wall. The movable bulkhead 4 at that end of the car is now shifted to a position against this 15 end box and bolted in the adjusted position to leave an empty space between the bulkhead 4 and partition 3 (see Figures I and IV). The loading of merchandise chamber 1 is now completed between the adjusted bulkhead 4 and the opposite 20 end wall of the chamber 1, which wall may or may not be constructed of nested sections in accordance with this invention. By adjusting the bulkhead 4 and altering the loading space so that it will conform to the requirement of the 25 shipment, shifting of the latter during transit is avoided. This construction eliminates the necessity for the usual and objectional temporary end brace, of so-called "2 by 4's" and wider facing strips, which ordinarily are nailed to the 30 vehicle structure. Make-shift braces of this nature are not suited for general use and are scrapped or discarded as waste at the point of destination of the shipment. Braces of this make-shift kind also, and not infrequently, cause 35 damage to the vehicle structure due to the nailing, and to the shipment in event of their becoming broken or loosened in use.

Where the shipment is designed for standard loading and/or will substantially fill the merchandise chamber 1, the bulkhead 4 may be stored by its placement and securing in nested relation with partition 3. In such position, bulkhead 4 and partition 3 form, in effect, a single, rigid wall structure and thus serve jointly to take the 45 thrust of the cargo loading, but with the bulkhead 4 directly taking the thrust of the load. If the partition 3 at no time contacts the shipment due to the use of the bulkhead as above indicated, it may be constructed, for the purposes of economy, of simple design and without reference to a requisite strength and resistance to thrust stresses imposed by the load, but merely to withstand the ice pressure in shifting shocks.

The invention offers the further advantage that 55 the wall structure, composed of its two sections 3 and 4, and the loading space of the merchandise chamber 1, when the bulkhead 4 is in stored position, may be of standard, A. A. R. over-all dimensions. In a very simple manner, therefore, 60 the invention provides for storage of the bulkhead at one end of the merchandise chamber so that the chamber is clear and suitable for standard loading and the length of the cargo space from the stored bulkhead 4 to the opposite end 65 of the chamber 1, as illustrated in Figure II, is in agreement with the standard dimensional specifications for the loading space of cars without stored or movable bulkheads.

While the above describes one method of use 70 of the movable bulkhead 4, other possible uses are readily apparent. The roller tracks 41, for example, may extend for any desired distance along the side walls of the loading space or compartment 1, or even continuously from end to 75

end of the merchandise chamber, and thus permit use of the bulkhead 4 as a load brace at the center of the car where it is desired to load from the ends of the lading space toward the center or doorway of the chamber 1. This type of bracing is sometimes used for shipments of crated peaches and the like. Where the bulkhead 4 is to be used at the center of the merchandise chamber, a sturdier construction may be required and 10 provided for the partition 3.

In one possible use of this invention, wall section 3 may constitute one of the end or side walls of the car. The drawings, however, show a preferred embodiment of the invention.

15 It will be understood that the foregoing description is illustrative, and that the appended claims are intended to cover such other embodiments as are within the scope of the invention.

We claim:

20 1. In a bulkhead or partition for use in the loading space of a railway or other vehicle, the combination comprising a two part structure, of which one part is fixed with reference to the vehicle and the other part is movable to adjusted 25 positions and in spaced relation to the fixed part, the juxtaposed faces of the two parts and their structural elements being so relatively arranged that they may be adjusted in a nesting relationship the combined thickness of the two parts in 30 said relationship being not substantially greater than that of a unitary structure of like strength and resistance to load and ice forces.

2. In a railway or other vehicle for transporting merchandise the combination comprising: a 35 merchandise chamber, and a bulkhead extending across the merchandise chamber and mounted for adjustment longitudinally thereof and to a position against the face of an inner end wall of the chamber, said bulkhead comprising means 40 presenting a substantially plane wall surface at its front side to the interior of the merchandise chamber and at its reverse side and projecting therefrom a series of spaced reinforcing elements, said inner end wall having set-back portions to 45 receive in nesting relation the said reinforcing elements of said bulkhead in its position of adjustment against said end wall, said bulkhead in said position of adjustment and the adjacent areas of the inner side walls of the merchandise 50 chamber providing substantially plane loading-space wall surfaces for the end of the merchandise chamber.

3. In a railway or other vehicle for transporting merchandise the combination comprising: a 55 merchandise chamber; a bulkhead extending across the merchandise chamber; means supporting said bulkhead in a substantially vertical position and providing for adjustment of the bulkhead along the chamber and to a position 60 against the face of an inner end wall of said merchandise chamber; and means to engage the vehicle structure for securing said bulkhead in its positions of adjustment; said bulkhead comprising means presenting a substantially plane 65 wall surface at its front side to the interior of the merchandise chamber, and means projecting from the reverse side of the bulkhead and providing a reinforcement therefor; said inner end wall having set-back portions to receive in 70 nesting relation the said projecting means of said bulkhead in its position of adjustment against said end wall; said bulkhead in said position of adjustment and the adjacent areas of the inner side walls of the merchandise chamber providing

substantially plane loading-space wall surfaces for the end of the merchandise chamber.

4. In a railway or other vehicle having side and end walls defining a merchandise chamber: the combination of a partition disposed transversely of the vehicle and fixed with relation to a wall thereof, said partition having members presenting spaced recesses in one face thereof, the depth of said recesses being approximately the same as the thickness of said partition; and 5 a bulkhead paralleling said fixed partition and shiftable toward and away therefrom, said bulkhead comprising means presenting a substantially plane wall surface, at its front face, and a number of spaced reinforcing bars projecting from 10 the reverse side of the bulkhead, said reinforcing bars being arranged as to spacing to be received within said recesses in the position of adjustment of said bulkhead against said partition.

15 5. In a railway car construction according to 20 claim 2, wherein the substantially plane wall surface of the bulkhead in the position of adjustment of the bulkhead against the inner end wall is spaced from the opposite loading space wall surface a distance defining the length of the 25 cargo space in substantial agreement with the standard dimensional specifications for the loading space of cars with fixed bulkheads.

6. In a railway car according to claim 2, wherein 30 in the projecting reinforcing elements are received wholly within said set-back portions and said projecting elements and said inner end wall are of substantially the same thickness.

7. In a railway car according to claim 2, wherein 35 in said inner end wall and the bulkhead in its position of adjustment thereagainst are in nested relation and together provide, in effect, a unitary reinforced end wall for the merchandise chamber.

8. In a railway or other vehicle for transporting 40 merchandise having at least two chambers, a bulkhead interposed between said chambers and comprising two parallel sections, one of which is adjustable with respect to the other lengthwise 45 of the car and having back-to-back relation in one position of adjustment to provide a single wall structure between said chambers, one of said sections having set-back portions, and the other of said sections having projecting reinforcing means positioned to register with and to be received within said set-back portions in the back-to-back position of adjustment of said sections.

9. In a railway car or other vehicle according 50 to claim 8, wherein the projecting reinforcing means are received wholly within the bulkhead section having the set-back portions, and said projecting means and said last-named bulkhead section are of substantially the same thickness.

10. In a railway or other vehicle having a merchandise chamber, a wall structure for said chamber comprising two interfitting parallel sections in back-to-back relation, one of the sections being movable relatively to the other to provide a bulkhead in a desired position of adjustment within the merchandise chamber, said sections in the interfitted relation providing a wall structure of a thickness approximating that of a conventional undivided wall structure for that part of the usual merchandise chamber.

11. In a railway or other vehicle for transporting 70 merchandise the combination comprising: a merchandise chamber having recessed opposite walls; tracks set in the recesses of said walls; a bulkhead extending between said opposite walls; rollers supporting said bulkhead and riding on 75

- said track to provide for adjustment of the bulkhead along the chamber and to a position against the face of an inner wall of said merchandise chamber; and bolts mounted on said bulkhead 5 and operable to engage the vehicle structure for securing said bulkhead in its positions of adjustment; said bulkhead comprising means presenting a substantially plane wall surface at its front side to the interior of the merchandise chamber, 10 and means projecting from the reverse side of the bulkhead and providing a reinforcement therefor; said inner wall of the merchandise chamber having set-back portions to receive in nesting relation the said projecting means of said bulkhead 15 in its position of adjustment against said inner wall.
12. In a railway or other vehicle for transporting merchandise the combination comprising: a merchandise chamber having its side walls, and 20 an end wall provided with recesses; a bulkhead having a plane wall surface at its front side and means projecting from its reverse side to provide a reinforcement therefor; and means providing for adjustment of the bulkhead along the chamber and to a position in which said projecting reinforcement is received in nesting relation within the recesses in said end wall; said adjustment means comprising rollers secured to the bulkhead, and tracks mounted in the recesses of said 25 side walls and supporting said rollers, said side wall recesses and tracks serving to confine said rollers to prevent accidental disengagement between said rollers and tracks.
13. In a railway or other vehicle for transporting merchandise the combination comprising: a merchandise chamber having its side walls and 30 an end wall provided with recesses; a bulkhead having a plane wall surface at its front side and means projecting from its reverse side to provide a reinforcement therefor; and means providing for adjustment of the bulkhead along the chamber and to a position in which said projecting reinforcement is received in nesting relation within the recesses in said end wall; said adjustment means comprising rollers secured to the bulkhead, and tracks mounted in the recesses of said side walls and supporting said rollers, said side wall recesses and tracks serving to confine said rollers to prevent accidental disengagement between said rollers and tracks.
14. In a railway or other vehicle for transporting merchandise the combination comprising: a merchandise chamber for loads of varying size, and a bulkhead extending across the chamber and mounted for adjustment longitudinally thereof to vary the loading space of said chamber in accordance with the requirement of the load, 20 said bulkhead being also adjustable to a stored position against the face of an inner end wall of said chamber, and comprising means presenting a substantially plane wall surface at its front side to the interior of the merchandise chamber and 25 at its reverse side and projecting therefrom a series of spaced reinforcing elements, said inner end wall having set-back portions to receive in nesting relation the said reinforcing elements of said bulkhead in its position of adjustment 30 against said end wall, said bulkhead in said position of adjustment and the adjacent areas of the inner side walls of the merchandise chamber providing substantially plane loading-space wall surfaces for the end of the merchandise chamber. 35
